 In Germany March 5, 1937

4 Claims. (Cl. 179—16)

The invention relates to a circuit arrangement for correcting impulses in remote control systems and in particular telephone systems. Various arrangements of this sort are already known but all these have the disadvantage that a considerable number of relays is required. Thus the known arrangements in addition to the impulse receiving relay and the impulse transmitting relay normally require a number and at any rate 10 at least one auxiliary relay.

The invention aims at reducing still further the number of switching means and achieves this object in that the correction of the impulses is effected by the impulse receiving relay and the 15 impulse transmitting relay which so mutually control one another that the receiving relay energized over the line energizes the transmitting relay in a local circuit, whereupon the transmitting relay disconnects the receiving relay from 20 the line and connects itself to the line circuit in place thereof.

The attached drawing represents an embodiment of the invention. The correcting device according to the invention is arranged in the repeater Ue_1 , which is disposed at the outgoing end of a connecting line VL . The repeater is seized when a calling subscriber establishes a call over a preselector VW and a final selector LW . The final selector is constructed as a so-called "final selector with switching through facilities" in order to make it possible in small exchanges to pass to another exchange over a connecting line. When the repeater Ue_1 is seized over the final selector LW relay A energizes over the closed loop to the calling subscriber in the following circuit: earth, winding III , winding II of relay A , contact $6h$, wiper b of the final selector LW and of the preselector VW , the subscriber's loop, wiper a of the pre-selector VW , wiper a of the final selector LW , contact $3h$, winding I of relay A , battery, earth. Relay A energizes and closes the following circuit for relay H : earth, contact $1a$, winding I of relay H , battery and earth. Relay H energizes and opens its contacts $3h$ and $6h$ and closes its contacts $5h$ and $2h$. These contacts are made as "make-before-break" contacts, i. e., contacts $5h$ and $2h$ close before the contacts $6h$ and $3h$ open, respectively. In place of relay A , relay 50 H now holds up over the subscriber's loop: earth, winding II of relay H , contact $5h$, wiper b of the final selector, wiper b of the preselector, the subscriber's loop, wiper a of the preselector, wiper a of the final selector, contact $2h$, winding I of relay H , battery, earth.

On seizure, the slow-to-operate seizing relay C , is also energized over the c -lead and wiper c of the final selector. Before it energizes, however, the switching operations just described in which relay H became energized have taken place. 5 Relay C closes its contacts $16c$ and $17c$ and thereby switches through the leads of the connecting line VL to the incoming repeater Ue_2 in the distant exchange. Since contact $14h$ has also been closed, the impulse receiving relay J in the 10 incoming repeater Ue_1 is now energized over the a -lead: earth, winding of relay J , a -lead of the line VL , contact $16c$ and $14h$, winding of relay Dr_1 , battery, earth. The control relay B of the incoming repeater Ue_2 is energized over the b - 15 lead: earth, winding of relay B , lead b , of the line VL , contact $17c$, winding of relay Dr_2 , battery, earth. The winding I of relay V of the repeater Ue_1 is for the moment still short-circuited over contacts $8c$ and $9h$. 20

When impulses are transmitted by the calling subscriber, the subscriber's loop is alternately opened and closed. When the loop is opened relay H releases. It interrupts the circuit for the receiving relay J in the incoming repeater Ue_2 25 at its contact $14h$. Relay J there extends the impulses in some manner with which we are not concerned, for example by breaking a loop. When relay H releases contact $2h$ and $5h$ are also opened and contacts $3h$ and $6h$ closed. 30 When at the end of the impulse the calling subscriber's loop is closed again, relay A first energizes again over the loop. Relay A energizes rapidly. In the event of the closing of the loop which in the present embodiment represents the 35 impulse pause, being very short, the relay is held energized after its initial energization in the following circuit: earth, contacts $4a$, $3h$, winding I of relay A , battery, earth. Relay A energizes and operates relay H over its contact $1a$ and winding I . In addition it short-circuits its own winding III over contacts $1a$ and the controlling resistance W_{11} . On account of this short circuit relay A is made slow-to-release and the extent of this effect can be adjusted by the variable 40 resistance W_{11} . After relay H has energized, relay A is disconnected from the subscriber's loop and in place of it relay H is connected to the loop over its windings I and II . Since it has been assumed that the closing of the loop is very brief, 45 relay H will not be held over the loop but on account of the slow-to-release feature of relay A it remains energized at first over contact $1a$. Only when relay A has released does relay H de-energize and extend the impulse by opening its 50 55

contact 14h. Relay A is now reconnected to the subscriber's loop in place of relay H.

If the next closing of the loop instead of being very short, as previously assumed, should be very long and the opening of the loop, i. e., the impulse should be short, relay A energizes first and after its release relay H is held energized over the subscriber's loop until the loop is interrupted. Since relay H is very quick to release, for example 5 ms. on account of a suitably arranged stop plate, and moreover after the interruption of the loop at first only relay A energizes and then in dependence thereupon relay H, a sufficient length is given to the extended impulse in spite of a very short breakage of the loop.

What is claimed is:

1. In an impulse correcting repeater arranged to receive series of impulses over a circuit and transmit corrected series of impulses, an impulse

receiving relay connected to said circuit and energized thereover, an impulse transmitting relay, a circuit controlled by the receiving relay for energizing said transmitting relay, and means controlled by the transmitting relay for disconnecting the receiving relay from the circuit and connecting the transmitting relay thereto.

2. A repeater as claimed in claim 1 in which the impulse receiving relay shunts one of its windings to make it slow to release.

3. A repeater as claimed in claim 1 in which the receiving relay has means for locking itself over a local circuit, after it is energized over the first circuit.

4. A repeater as claimed in claim 1 in which the receiving relay when closing the circuit of the transmitting relay shunts one of its own windings and closes a local locking circuit for itself.
